UNITED STATES PATENT OFFICE.

JUDSON McFELL, OF CHICAGO, ILLINOIS.

SELECTIVE SIGNALING MEANS.

1,095,655.

Specification of Letters Patent.

Patented May 5, 1914.

Application filed July 27, 1910. Serial No. 574,158.

To all whom it may concern:

Be it known that I, JUDSON McFELL, a citizen of the United States, residing at Chicago, in the county of Cook and State 5 of Illinois, have invented certain new and useful Improvements in Selective Signaling Means, of which the following is a specification.

My invention relates to improvements in 10 selective signaling means, such for instance as may be employed in conjunction with telephone apparatus, in order that the station of some desired party upon a line common to a number of parties may selectively 15 be called, to the exclusion of all others.

The general object of my invention is to 20 provide a signaling system, whereby a selector device at any one of a plurality of signal receiving stations on the line may selectively be caused to condition for operation 25 an annunciator at that station in response to the transmission over the line wire of signaling impulses grouped to constitute a plural digit number signal for which the selector is structurally set.

A more specific object of my invention is 30 to provide in such a system a selector containing a step-up device which advances and dwells in harmony with the impulse groups and dwells between impulse groups. occasioned in the line by the transmitting 35 apparatus, and containing electrically operated controlling means to condition the annunciator for operation only as a result of dwells between impulse groups coincident with critical positions of the step up device.

Many other objects of my invention will 40 become apparent from the following description, taken in conjunction with the accompanying drawings, in which;

Figure 1 shows in front elevation a selector apparatus, in connection with its wiring diagrammatically indicated. Fig. 1^a, is 45 a small wiring diagram. Fig. 2 is a section on line 2—2 of Fig. 1; Fig. 3 is an isometric detail of the selector apparatus; Fig. 4 is a section on line 4—4 of Fig. 2, and; Figs. 5 and 6 are a section on line 5—5 of Fig. 1, 50 and a perspective detail respectively, showing fragmentary parts of the selector apparatus.

In Fig. 1, of the drawings, 10 and 11 indicate line wires, forming part of the signaling circuit, which is herein illustratively shown as a normally open circuit, such as

may conveniently be used in a train dispatcher's telephone-signal system, wherein the transmitting apparatus is located at one station only.

12 indicates a source of current supply for 60 the line wires, and 13 indicates in general a transmitter. The transmitter is shown only diagrammatically in Fig. 1, details of a construction suitable for employment being 65 shown and described in my copending application, Serial No. 556,404, filed April 19, 1910. The transmitter apparatus, shown in Fig. 1, comprises a line switch 14, normally open, and controlled by a signal 70 wheel, 15, having a suitably notched periphery into the notches of which the long arm of the switch, 14, may descend to close the circuit, said wheel standing normally in position to raise the arm of the switch and 75 open the circuit. The wheel 15 may be driven by any suitable clock-work mechanism, or other motor device, arranged in the casing 16, the arrangement being preferably such that the wheel 15 makes one complete revolution for every signal transmitted.

Spacers 17 and 18 are provided in arrangement to be shifted upon the wheel to 80 close any desired notch thereof, such spacers being shiftable by handles 17' and 18'. In the arrangement shown the spacers, 17 and 18, are respectively arranged to close the 5th., and 10th., spaces of the wheel, so that when the latter is rotated in the direction 90 indicated by the arrow, four notches pass the switch 14, then spacer 17 holds the switch open during the passage of the arc of one notch, then four more closures of the switch occur, then the switch is again 95 held open by the second spacer 18, then an arbitrary group of closures of the switch 14 occurs, this being the arrangement appropriate to send the code number 44.

In general, therefore, it will be observed, 100 that the transmitting apparatus can preferably be of a motor driven construction which may be set to send any code number within an appropriate range, such number preferably consisting of a plurality of impulse groups, the unbroken series of impulses of each group constituting a digit corresponding with the number of impulses thereof, and each digit group being followed by a dwell or cessation of the impulses, and the number signal followed by 110 an arbitrary series of impulses, making the

total quantity of impulses some definite amount.

It will become apparent that the device might be operated with an ordinary telegraph key as a transmitter, but owing to the fact that the time interval between impulses is of importance in the operation of the selector device at the signal receiving stations, a motor driven transmitter is 10 greatly to be preferred on account of the regularity of its spacing of impulses in the transmission of digit-groups.

It will be understood that by the term impulses as herein employed, I mean such impulsive changes in the condition of the line as may actuate appropriate electro-responsive devices, such as an electro-magnet; and it will further be understood, that the showing of the devices as applied to an open 20 circuit system is made for simplicity only, without intent to limit the application of my invention to the particular wiring arrangement shown.

At each subscriber's station I provide a 25 selector, generally indicated at 20, and as part of such selector apparatus I provide an electro-responsive impulse-receiving device, as an electro-magnet, 21, shown as bridged on the line, responsive to the current impulses therein. The electro-magnet 21 in the embodiment herein shown has its armature 22 connected to a pivoted bell crank lever 23, the long arm of which carries an actuating pawl, 24, for a ratchet wheel, 25, 30 constituting a primary step-up controller device, or moving part of the selector, the pawl 24 being so arranged that when the armature 22 is retracted, it stands out of engagement with the teeth of the ratchet.

40 The ratchet wheel shaft is mounted in bearings in a suitable base plate, 26, and bracket arm, 27, and is acted upon by a return spring, 28, the wheel being acted upon by a holding pawl, 29, pivotally mounted, having a tail portion 29^a, and having depending below its pivotal axis a pin 29^b, by which the release operation to permit spring return of the ratchet may be effected, as hereinafter described.

50 The annunciator apparatus, herein shown as a bell, or gong, to be more fully described, is arranged to be conditioned for operation only by a plurality of steps or operations in a secondary controlling apparatus, such 55 controlling apparatus being in turn governed by the primary step-up controller or device, so that each functional step of the annunciator controlling means is possible only when the primary device is in certain critical positions for which it is structurally set. Further, the secondary controlling means is arranged for control by an electrical timing switch, actuated by the impulse receiver, so that a dwell in the operation of 60 the electro-responsive device, 21, concurrent

with the attainment of the critical position of the step-up device 25 is prerequisite to each functional operation of said governing apparatus.

Specifically, 30 indicates a gong having 70 its clapper 31, depending from the shaft 32 extending through the frame of the device, and provided with a finger, 33, arranged to be operated by a lateral projection, 34, upon the extremity of the arm, 34, pivoted as 75 at 35, to the long arm of the bell crank lever, 23. The arm, 34, normally stands in such position that it may freely move below and out of contact with the finger 33, but its elevation is controlled by a lever 36 bearing at its end a wheel, 36', upon which the arm, 34, rests, said lever 36 being rigidly connected for movement with a secondary step-up device or ratchet-sector, 37, pivotally mounted between the base plate 26, and 80 the bracket, 27'. This secondary-step-up ratchet, 37, stands normally in a position governed by contact of its stop pin 38 with the bracket 27', and is preferably provided with two teeth for an active pawl, and suitable teeth for a retaining pawl. The active pawl, 40, is carried by an armature lever, 41, weighted at 41' for gravity-retraction, having at its opposite extremity an armature 42 for a controlling electro-magnet, 43, and a 90 holding pawl, 44, is mounted between the plate 26 and bracket 27', and normally maintained in active position by the weight of its tail portion 44'. If the secondary ratchet 37 is advanced two steps the rotary 100 displacement of the lever arm 36 lifts the arm 34 to such position that its projection, 34', stands opposed to the lower extremity of the finger 33 for the gong clapper, so that thereafter vibration of the bell-crank lever, 105 23, due to impulsive energization of electro-magnet 21, will cause the gong to sound at each impulse. Thus the arm 34 is a part to be moved to condition the annunciator for operation by the line magnet, functionally 110 positioned only by a plurality of steps of the governing ratchet, 37, and the latter is actuated by the controlling magnet, 43, only when dwells in the signal impulses coincide with specific positions of the step-up wheel, 115 25, as will now be made to appear.

The electric circuit for the controlling magnet, 43, depends for each closure upon contacts controlled by the primary ratchet 25. To this end, I mount upon the ratchet 120 wheel, 25, an insulated contact, 47, projecting at right angles to the surface of the wheel, and suitably mount upon a supporting structure, stationary contacts 48, 48', and 49. The two contacts, 48 and 48', are 125 spaced apart from each other and from the starting point of the moving contact, 47, according to the number for which the selector is set to respond, that is to say, at station No. "44", herein taken as typical, the 130

first contact 48 is four steps removed from the normal position of the moving contact, 47, and the contact 48' is four steps removed from the first said contact, 48. As a matter 5 of convenient construction, I make the contact members, 48, 48', and 49, in the form of long spring fingers, mounted in electrical contact with each other and with the plate 50, all insulated from the supporting post, 10 51, projecting from the bracket, 27. The plate 50 is of sector form, provided with notches, 53, in its periphery, arranged to be engaged by tongues, 54, upon their respective contact member 48, 48' and 49. As the 15 notches 53 in the construction shown are arranged proportionately to the teeth of the ratchet 25, the contacts 48 and 48' may readily be adjusted to positions corresponding with different desired numbers and when 20 once adjusted will remain fixed in position by reason of the engagement of tongues 54 with the notches 53.

I also provide for the secondary controller a timing means functionally responsive 25 to dwells in the operation of the impulse receiver, and to this end I arrange in the circuit of the controlling magnet, 43, a switch governed by the armature lever, 23, such switch, generally indicated at 56, comprising 30 a stationary contact, 57, and a movable contact, 58, the latter normally pressed into engagement with the former by an insulated projection upon the armature lever 23.

The complete circuit for the magnet 43 35 comprises a battery 60 having one terminal connected by wire 61 with the magnet 43, which in turn is connected by wire 62 with a connecting bar, 50', connected to and preferably formed integral with the plate 50, 40 the movable contact 47 on the wheel having connection by wire 63 with the switch spring 58 of switch 56, the stationary contact, 57, of said switch having connection by wire 64 to the remaining terminal of battery 60.

45 The secondary, or controlling magnet 43 is preferably a slow-acting, or sluggish coil, requiring for its energization the application of current for a relatively great length of time, say by way of example, an eighth of a second. It will, therefore, be apparent that in order that the magnet 43 may effectually be energized the battery circuit 60, 61, 62, 63, 64, must be closed and remain closed for say an eighth of a second, these conditions 50 necessitating that moving contact 47 of the step-up wheel 25, be in coöperating position with respect to one of its stationary contacts 48, etc., and that the switch 56 shall coincidentally remain closed for the critical 55 time. Now, it may be explained, the transmitter is run to send impulses at the rate of say eight a second, so that whenever one of its notches is filled by a spacer 17 or 18, and fails to permit the closure of the circuit, 60 a break in the impulse series of more than

an eighth of a second duration occurs. Consequently, as long as an uninterrupted series of impulses constituting a number digit are in transmission over the line, the armature lever 23 of the electro-responsive device 21 70 vibrates at the rate of approximately eight times a second, and the switch 56, closed only at the extreme end of the excursion of the lever 23, is opened during the greater part of each such impulse period. In consequence 75 it will appear, so long as an uninterrupted series of impulses is transmitted over the line from one of the timed transmitters, no magnet 43 at any station can effectively be energized, because, although at one or all of 80 the stations contact 47 may make connection with contact 48 and 48' during the time of transmission of such uninterrupted series of impulses, the switch 56 does not stay closed at any time for a period of sufficient 85 duration to enable the magnet 43 to become effectively energized, so long as there is no dwell or interruption in the impulse series. If, on the other hand, at the time when contact 47 stands in engagement with one of its 90 stationary contacts, the impulse series is interrupted and a dwell occurs in the operation of the electro-responsive device at a signaling station, the switch 56 is closed for the relatively long period of a little more 95 than one impulse space, and this, as above explained, is sufficient to permit the battery 60 effectively to energize the magnet 43, through the circuit 60, 62, 63, 64, including the closed switch 56, and including also a 100 closed connection between movable contact 47 and its coöperating stationary contact. It will be seen that by the simple expedient of making the magnet 43 slow-acting I make it non-responsive to abbreviated closures of 105 switch 56, and so can operate without mechanical retardation of the back stroke of the armature lever 23, the present arrangement being chosen for its simplicity.

In general it will be seen that with the apparatus illustrated in Fig. 1, the transmission of a signal "44" will result as follows: As the first four impulses act upon the electro-responsive device, 21, its armature lever, 23, and live pawl 24 steps forward the 115 ratchet wheel, 25, four steps, thereby positioning movable contact, 47, to coöperate with stationary contact 48. Then occurs a dwell, or interruption, of the impulse series due to the passage of the spacer 17 beneath 120 the switch 14. During the dwell the armature lever 23 stands in the position shown in Fig. 1 closing the switch 56. These conditions result in the energization of the controlling magnet 43 through the circuit 61, 125 62, 63, 64, heretofore described, and consequently said magnet 43 attracts its armature 42, the lever 41 whereof, through pawl 40, advances a secondary ratchet 37 one step. This advancement of the ratchet 37 raises 130

the arm 36 somewhat, but not enough to produce any functional results. Following the dwell occasioned by the spacer 17, a second series of four impulses occurs, and accordingly the ratchet 25 of the station apparatus is advanced in the manner before stated, to bring contact 47 beneath the second stationary contact member 48', and here again a dwell occurs due to the passage of spacer 18 past the switch 14. During this second dwell the magnet 43 is again energized, and again the secondary ratchet 37 is advanced a step. This second advancement of the ratchet raises lever 36, so that the arm 34 is elevated to bring its finger 34' into its operative plane in register with the lower end of finger 33, of the bell clapper. Following this second dwell occur a series of arbitrary impulses, each of which occasions the vibration of armature lever, 23, and consequently causes armature lever 34 to move the finger 33, thereby to ring the gong with each impulse. The total number of impulses transmitted is sufficient to bring the movable contact 47 of the ratchet 25, into engagement with the stationary contact 49 and then, as the impulse ceases altogether by reason of the transmitter coming to a standstill, the magnet 43 is a third time engaged, this time for releasing purposes.

To release the holding dog for the primary step-up device 25, I provide a hook member 70 pivoted to the armature lever 41, standing normally with its stop end 71 holding it in position such that its hook end 72 stands below the pin 29' connected with the holding pawl, 29. The lower face of said member 70 is so shaped as to receive and be lifted by a roller 73 carried by the wheel 25, during the steps which accompany the arbitrary impulses of the signal transmitted, such raising of the member 70 throwing its end 72 into operative engagement with the pin 29'. Consequently, when following the arbitrary impulses which have brought this engagement of parts 72 and 29' about, the armature lever 41 moves to the right the hook 70 moves the pin 29' to the right, throwing the pawl 29 to releasing position, and so permitting the ratchet wheel 25 to return to normal position under the influence of its spring. As the pawl 29 is thus thrown to inoperative position, its tail 29a is engaged and locked by gravity latch 75, carried by the frame, and the pawl is maintained latched in inoperative position until the pin 76 carried by the wheel 25 strikes the latch 75 and moves it to releasing position just as the wheel 25 reaches its normal or initial position. The wheel 25 likewise carries a small gravity trigger, 77, which in the forward rotation of the wheel has its weighted extremity, 77', pass idly by the tail 44' of holding pawl 44 for the secondary ratchet, but on the return movement of the ratchet

wheel 25, this trigger end 77', strikes the tail 44' of holding pawl 44 and thereby releases the secondary ratchet for gravity return to initial position, so effecting complete restoration of all of the parts to normal position after the transmission of the signal.

In order to provide simple means available where desired to enable the signaling party to determine whether the annunciator at the particular station which he is calling is being duly operated, I provide answer-back means as follows: Upon the arm 34 I provide a projection 80 to coöperate, but only when the arm 34 is raised, with a switch 81 to close said switch on the back stroke or retraction of the armature lever, 23. One member of this switch I wire as at 82 to a suitable battery, 82', and the line 10. The battery 82' may be the transmitter battery of the telephone apparatus (not shown) at the receiving station, or any other battery may be used. The other member of the switch is connected by wire 83 with a stationary contact point 84, suitably disposed to co-operate with a series of contacts 85, carried in insulated fashion by the wheel 25, and having connection by wire 86 through a resistance coil 87 to the wire 11 of the line. The contacts 85 may be arranged appropriately to represent the number of the station to which its selector responds, and such contacts 85 are disposed so that they coöperate with their stationary contact 84 during the period of time when the arbitrary impulses are being transmitted. These contacts 85 may be arranged so that those constituting a digit are spaced apart by an arc corresponding with say two teeth of the ratchet 25 or any other desired regular number of teeth, the distance between the groups representing digits of course being greater. Now it will be seen that at the station where the series of impulses is causing the operation of the annunciator, and at that station only, the battery 82' is caused to impress its potential upon the line during each return movement of the armature 23, which occurs with the closing of the switch contacts 84 and 85. Obviously, this potentiation of the line at the time when the line circuit is broken at switch 14, may be detected in a telephone receiver operatively connected in the line, as diagrammatically indicated at 90 in Fig. 1a. Obviously, the answer-back feature is a refinement which may be omitted if desired.

Many of the broad ideas embodied in the apparatus herein shown and described are likewise shown and are broadly claimed in co-pending applications, Serial Nos. 556403 and 574157 but

What I herein claim and desire to secure by Letters Patent is;

1. Selective signaling means comprising in combination, a primary electro-responsive device having an armature, a step-up mech-

- anism advanced thereby in a series of equal steps, a secondary-electro-responsive device, a part moved thereby through a plurality of steps, a signaling means controlled by said plurality of steps of said secondary device, and means controlling said secondary electro-responsive device comprising switch means operated in successive positions respectively of the primary step-up-mechanism, and another switch-means controlled by the armature of the primary electro-responsive device. 5
2. Selective signaling means comprising a part to be moved, an annunciator controlled by said part, a secondary electro-responsive actuating means to effect a plurality of movements of said part to dispose it for operation, a primary electro-responsive device having a vibrating armature part, a step-up device actuated thereby, and controlling means for the secondary electro-responsive actuating means comprising a plurality of switches closable by the step-up device in different number-indicating positions and a switch controlled by the position of the vibrating armature part of the primary-electro-responsive device. 10
3. Selective signaling means comprising a part to be moved through a plurality of steps, a secondary electro-responsive means for actuating said part successively through its steps, a primary electro-responsive means, a step-up device operated by said primary electro-responsive means to advance step by step, appropriate circuit connections for said primary and said secondary responsive means, and means responsive to successive predetermined positions of the step-up device, and to duration of the dwells of said 15 primary electro responsive means when said step-up device is in said positions, controlling the successive operations of the said secondary electro-responsive means. 20
4. Selective signaling means, comprising a part to be moved, a primary electro-responsive device, step-up means operated thereby, secondary electro-responsive means for moving said part to be moved through a plurality of steps, a switch controlled by the primary electro-responsive device, regardless of the position of the step-up means, other switches controlled by successive positions of the step-up means, and circuit connections for said secondary electro-responsive means including in series a step-up controlled switch and the first-mentioned switch. 25
5. The combination of a movable part to be positioned for operation; primary means including a single step up device and a vibrating part for actuating said step up device by its advances; and secondary means controlled by said step-up device and said vibrating part jointly, and responding only to dwells between the advances of said vibrating part concurrent with predetermined 30
- positions of said step-up device, said secondary means including a moving part acting, upon a plurality of operations, to move the first mentioned movable part to its position for operation and means controlled by said vibrating part and in turn controlling said moving means. 70
6. The combination of a primary electro-responsive device, a step-up device, arranged for operation thereby, a secondary electro-responsive device, a circuit therefor controlled in part by the position of the step-up device and including contact devices arranged to be changed from normal relation at a plurality of positions of the step-up device respectively, switching mechanism in said circuit timed by the operation of the primary electro-responsive device, and working parts operatively associated with said secondary responsive device to be conditioned for operation by a plurality of operations thereof. 75
7. The combination of a primary magnet, having a vibrating armature, a secondary slow-acting magnet, a switch controlled by the operation of said armature of the primary magnet, a step-up device controlled by said armature, switch means controlled by said step-up device and arranged for operation at successive points respectively in the movement of said step-up device, a circuit for the secondary magnet including said switches, and mechanism arranged to be conditioned for operation by a plurality of operations of the secondary magnet. 80
8. Selective signaling means comprising an impulse receiving magnet, a step-up device actuated thereby, an annunciator, a part movable to position to operate the annunciator from the primary magnet, means including a secondary magnet for so moving said part to said position, and a circuit for the secondary magnet controlled by said step-up device. 85
9. Selective signaling mechanism combining a primary magnet, having a vibrating armature, a switch arranged to be closed only when said armature is in one extreme of position, a step-up device for actuation by said armature, switching mechanism arranged to be closed a plurality of times during a movement of said step-up device, a secondary electro-magnet, a circuit therefor including both the armature-operated switch and the switching mechanism of the step-up device; and a working part controlled by the secondary electro-magnet. 90
10. Selective signaling means comprising a self-restoring step-up device, a primary electro-responsive actuating device therefor, switch means closable by said step-up device at predetermined points, a switch controlled by the primary electro-responsive device, a secondary electro-responsive controlling device, a circuit therefor controlled concur- 105
- 110
- 115
- 120
- 125
- 130

rently by the switch means associated with the step-up device and the switch associated with the primary electro-responsive device and a part to be moved associated with said 5 secondary electro-responsive device.

11. Selective signaling means comprising an impulse receiving magnet, a step-up device actuated thereby, an annunciator, a part movable to position to operate the annunciator 10 from said magnet, and electro-responsive means for moving said part to said position controlled by said step-up device.

12. The combination of a movable part to be positioned for operation, secondary electro-responsive moving means therefor operable through successive steps to position 15 said part for its operation; a single step-up

device controlling said moving means to permit movement thereof only in certain successive positions of the step-up device, a vibrating part for actuating said step-up device, primary electro-responsive means for actuating said vibrating part, said secondary electro-responsive moving means responding only to dwells in the primary electro-responsive device and including means controlled by said vibrating part and in turn controlling said moving means. 20 25

In testimony whereof I hereunto set my hand in the presence of two witnesses.

JUDSON McFELL.

In the presence of—
